UNITED STATES PATENT OFFICE.

HARRY BUDD ALLEN, OF ELMIRA, NEW YORK, ASSIGNOR TO F. M. HOWELL & CO.,
OF ELMIRA, NEW YORK, A CORPORATION OF NEW YORK.

FOLDING PAPER BOX, BOX CORNER, AND BLANK THEREFOR.

1,411,555.

Specification of Letters Patent.

Patented Apr. 4, 1922.

Application filed April 8, 1921. Serial No. 459,622.

To all whom it may concern:

Be it known that I, HARRY BUDD ALLEN, a citizen of the United States, residing at Elmira, in the county of Chemung and State 5 of New York, have invented certain new and useful Improvements in Folding Paper Boxes, Box Corners, and Blanks Therefor; and I hereby declare that the following is a full, clear, and exact description thereof, 10 reference being had to the accompanying drawings, which form part of this specification.

My invention relates to folding paper boxes, and box corners and blanks for forming the same.

The object of my invention is to improve, simplify, and cheapen the cost of construction, to eliminate waste incident to shaping the folds and fastenings provided for in the 20 blank from which the box is set up.

It is also my object to provide an improved rectangular box-corner designed to form an integral union of bottom, sides, and embody therein a fastener to hold said 25 parts together at right-angles to each other.

In the accompanying drawings forming a part of this specification Figure 1, is a plan view of a blank for the box. Figure 2 is a perspective view of the box, and Figure 3, is a detail of the box corner.

Referring more particularly to the drawings: A, denotes the bottom of the box. B, B, the ends, and C, C, the sides of the box. The ends B, B, terminate in tongues 35 b, b, b, b, and each tongue is slit or bifurcated forming latches b' adapted to overlap by forming at the base of each latch scores b², b², formed in the tongues b below said slits; said scores being projected at obtuse angles 40 to said slits in opposed diagonal lines below the base of each latch, as shown in the drawings. The purpose of said scores is to facilitate the lapping of one latch over the other without danger of tearing off the latches, 45 and moreover said scores affect the spreading of the latches apart after they have been passed through slits c located in the sides C adjacent the corners, and which are designed of a width to receive the latches when folded one over the other, and when spread apart to afford a hold for the latch dogs b³.

The box and corners are readily set up

from the blank by folding the sides at right-angles to the bottom, likewise the ends; the tongue latches are thus presented opposite 55 the slit in sides B and manipulated from the outside of the box. The folds to form the corner are manipulated as follows, first the side C containing slit c is folded at right-angles to the bottom A, then the end B is 60 likewise folded and the tongue b passed outside around the corner thus formed in outline. In this position the ends of the latches b' will project beyond slit c while the locking edges of dogs b³ will meet said 65 slit c. The latches b' b' are then pushed back until their ends meet slit c preparatory to their entrance therethrough. The effect of said backward movement of latches b' b' will cause the body of the tongue and base 70 of the latches to be raised upward in tent-like shape following the lines of the diagonal scores b², b², said diagonal scores being designed to allow and facilitate said movement of the tongue. The dogs b³ b³ are 75 then overlapped, directed to the slit c and then forced forward through slit c by pressing down upon the said raised portion of the tongue.

I claim—

1. A collapsible box-corner formed of a blank embracing in integral relation the bottom, a slotted side, and an end portion terminating in a divided tongue which tongue divisions are adapted to overlap each other and enter said slotted side; said end portion having scores positioned at an obtuse-angle to the base of each tongue division, said bottom, sides, and ends being adapted to fold at right-angles each to the 85 other.

2. In a fastener made of sheet material, a tongue slit longitudinally to form latches and scored at an obtuse angle to the slit, and a member having a slit to receive the 95 tongue.

3. In a fastener for paper receptacles a tongue slit to form two latches, said latches scored diagonally adapting them to overlap each other.

In testimony that I claim the foregoing as my own, I affix my signature.

HARRY BUDD ALLEN.
